UNITED STATES PATENT OFFICE.

EDWARD A. DE BLOIS, OF HARTFORD, CONNECTICUT.

DESIGN FOR A GARMENT-SUPPORT.

SPECIFICATION forming part of Design No. 34,224, dated March 12, 1901.

Application filed February 16, 1901. Serial No. 47,707. Term of patent 7 years.

To all whom it may concern:

Be it known that I, EDWARD A. DE BLOIS, a citizen of the United States, residing at Hartford, in the county of Hartford and State of Connecticut, have invented and produced a new and original Design for a Garment-Support, of which the following is a specification.

Figure 1 of the accompanying drawings, which form a part of the specification, is a side elevation of a garment-hanger embodying my design; and Fig. 2 is a plan view of the same.

As shown in the drawings, the leading or material feature of my design is the flat horizontally-extending doubled portion of the garment-support that depends from and lies beneath the outwardly and downwardly curved loops. The loops 3, that extend outwardly from the middle of the support, curve down-

wardly and are largest in diameter near their outer ends. The doubled portion 4 extends back and forth several times in a flat horizontal plane below the middle of the garment-support. The connection 5 extends vertically from the middle of the loops to one-half the distance between the ends of the flat horizontally-doubled portion of the garment-support. The portion 6 curves backwardly and upwardly and then downwardly above the middle of the loops.

Having described my invention, what I claim as new, and desire to secure by Letters Patent, is—

The design for a garment-support as herein shown and described.

EDWARD A. DE BLOIS.
